(57) **CLAIM**

The ornamental design for a hitch mountable cargo carrier, as shown and described.

DESCRIPTION

FIG. 1 is a perspective view of the hitch mountable cargo carrier showing our new design;

FIG. 2 is an enlarged top plan view thereof;

FIG. 3 is an enlarged rear elevational view thereof;

FIG. 4 is an enlarged bottom plan view thereof;

FIG. 5 is an enlarged left side elevational view thereof, the right side being a mirror image of the left shown; and,

FIG. 6 is an enlarged front elevational view thereof.
